ELECTRIC DISCHARGE DEVICE.

Application filed December 20, 1926. Serial No. 155,842.

This invention relates to electrical discharge devices of the type employing ionized gas, and more particularly to rectifiers for alternating current.

5 Some of the objects of the present invention are to simplify the construction of electrical discharge devices of the gas filled type; to increase the efficiency of operation of said devices; to increase the reliability and uniformity of their operation; to reduce the time required for aging said devices to insure uniform operation; and to lower the impedance of devices of the kind referred to.

In accordance with one aspect of the present invention, a vessel is filled with an ionizable gas and contains an anode and a cathode having a minimum separation therebetween, preferably of the order of several times the mean free path of electrons in the gas within 20 the vessel and preferably less than fifty times said path, the maximum separation between the active portions of the anode and cathode being a multiple of the minimum distance therebetween.

25 By filling the vessel with a gas of the helium group at a temperature in the vicinity of 25 degrees centigrade at a pressure of from 2 to 20 millimetres of mercury, efficient operating conditions may be obtained when the 30 electrodes are spaced apart in the manner described.

An important feature of the present invention consists in providing a cathode disk with means at its periphery for controlling the stability, uniformity and intensity of the electrical discharge between the electrodes. An edge of the disk turned up around the electron emitting portion thereof reinforces the disk and holds it in shape during and after 40 high temperature treatment thereof, the edge being so shaped by denting as to control the discharge between the electrodes.

These and other objects and features of the invention will be understood more clearly 45 from the following detailed description in connection with the accompanying drawing, in which:

Fig. 1 is a vertical section of an electrical discharge device, taken on line 1—1 of Fig. 2; 50 Fig. 2 is a plan of the electrode structure;

Figs. 3 and 4 are vertical sections of modifications of the cathode rim shown in Fig. 1;

Figs. 5 and 6 are a plan and elevation, respectively, showing a different method of arranging the electrode structure;

55 Figs. 7 and 8 are a plan and elevation, respectively, of a cathode having a wing normal thereto;

Figs. 9 and 10 are a plan and sectional elevation, respectively, of a cathode having a wing mounted at an acute angle therewith;

Fig. 11 is a sectional elevation of a modification of Fig. 10;

Figs. 12 and 13 are a plan and elevation, respectively, of a cathode having an auxiliary 65 element to supplement the action of the cathode; and

Figs. 14 and 15 are a plan and elevation, respectively, of a different modification of the electrode structure.

In Fig. 1, the envelope or vessel 1, of glass or other suitable material, contains an ionizable gas, preferably of the helium group, for example argon, helium or neon, or a suitable mixture thereof. The pressure of the gas 75 within the vessel is preferably in the vicinity of from 2 to 20 millimetres of mercury when filled at a temperature in the vicinity of 25 degrees centigrade, but may be somewhat above or below these limits.

The press 2 within the vessel supports the hollow stems 3, one being shown in full elevation and the other in section in Fig. 1, the stems being of glass or other suitable electric insulating material. A sleeve 4 of lava, or 85 other suitable refractory insulating material, having its lower end fitting coaxially over the free end of each stem 3, is provided with a constricted portion 5 forming a ledge resting on the free end of stem 3 and adapted 90 for holding the elongate anode wire 6 coaxially therewith. Anode 6 of manganese steel, nickel or other suitable material, has an electron receiving surface 7 at the upper end thereof within sleeve 4 and spaced from the 95 upper end of the sleeve by a distance preferably greater than the mean free path of electrons in the gas in vessel 1. An annular space 8 is preferably provided between the upper or free end of anode 6 and the inner wall of 100

sleeve 4, a recess 9 of larger diameter than space 8, being provided above the free end of the anode in the sleeve.

A cathode 11, of manganese steel, nickel 5 or other suitable material, is preferably in the form of a sheet or plate, and in the modification shown as illustrative of the invention, the cathode is in the form of a disk. The cathode is preferably of such size in relation to the electrode spacings that the maximum separation between the active portions of the anode and cathode is a multiple of the minimum distance therebetween. Cathode 11, is positioned laterally over sleeves 4 and 15 anodes 7, the disk resting on the ends of the sleeves and having a pair of thimbles 12 fitting over the free ends of the sleeves, each thimble being coaxial with one of the anodes 6. It will be noted that thimbles 12 are 20 formed in the sheet metal of the disk. In the modification illustrated by way of example in Figs. 1 and 2, the thimbles are connected by a bridge 13 for constructional reasons, so that the two thimbles may be looked upon as being 25 a single thimble when taken as a whole. A separate perforation 14, of slightly larger diameter than anodes 6, is provided in the disk coaxially over each anode 6.

A stay wire 15 sealed into press 2 normal 30 to cathode disk 11 is secured to the disk to hold it from moving axially of anodes 6 and sleeves 4, the thimbles 12 serving to hold disk 11 from moving laterally to sleeves 4 so that perforations 14 are retained in coaxial relationship with anodes 6. It will be noted that perforation 14 are positioned centrally in disk 11 and symmetrically disposed therein, the stay wire 15 being anchored to the center of the disk between perforations 14.

40 A U shaped channel 16 is spot welded or otherwise secured at the bottom of the U to disk 11, the arms of the U being spot welded to opposite sides of the wire 15 which pierces a hole in disk 11 and the bottom of the U shaped member. This form of construction makes it possible to make adjustment for any variations in the dimensions of the electrode structure so that disk 11 may be placed firmly against the free ends of sleeves 4 and there 45 held in place by welding element 16 to wire 15. Obviously wire 15 may be butt welded to disk 11, it being necessary, however, in such cases to trim wire 15 so that it just extends to the bottom surface of disk 11 when welded.

55 The upper surface of disk 11 is preferably coated with an active electron emitting substance such for example as the oxides of barium or strontium. An edge or flange 17 is turned up around the electron emitting surface 60 of the cathode for the purpose of reinforcing the cathode, particularly during and after baking the cathode at high temperature by a high frequency magnetic field directed axially of the disk. The 65 flange 17 constitutes a concentrated means

at the periphery of the cathode for controlling the discharge between the electrodes. It has been found that more uniform heat treatment of the disk and of the coating thereon may be obtained by denting the rim 70 at one or more places 18, the effect apparently being to reduce the heating of the peripheral portions of the disk in comparison with the heating when it is not dented, so that the peripheral portions are not too strongly heated 75 in comparison with the portions nearer the center of the disk.

The described relation of electrode spacings to the mean free path of electrons in the gaseous filling, gives rise to high conductivity 80 between one of the electrodes 6 and electrode 11, when said electrode 6 is positive with respect to electrode 11 and gives rise to relatively low conductivity or open circuit conditions when the potentials of the electrodes are reversed. It is thus possible to efficiently rectify alternating current.

Dents 18 in rim 17 of the disk appear to increase the reliability and uniformity of operation of the device. When first starting 90 rectifying action after completing the construction of the rectifier, the dents appear to function in such a manner as to reduce the time required to age the rectifier. For example, in certain instances where no dents 95 have been provided, several hours of continuous operation of the rectifier have been necessary before the action of the rectifier became stabilized so that a uniform current could be obtained therefrom, whereas in a rectifier in 100 which dents 18 are provided, the necessary aging may be accomplished quite consistently within from 30 to 60 seconds, thus greatly expediting the manufacture of the rectifiers.

A further advantage in the use of dents 18 appears to be in localizing the discharge between the electrodes and in preventing the occurrence of discharges which often prevent successful operation of rectifiers where nothing corresponding in function to dents 18 are 105 present. By localizing the discharge between the electrodes a more intense electron emission is obtained from the cathode and consequently a lower impedance is obtained between a given pair of electrodes. Owing to the low 110 impedance of the device, the energy losses are small and the efficiency is correspondingly high.

Fig. 3 shows an undented cathode rim 19 which may be employed in place of rim 17 115 Fig. 1. Fig. 4 shows an alternative form of cathode rim 20 in which the edge is rolled over inwardly on the electron emitting side of the cathode disk.

In Figs. 5 and 6 the cathode disk 11, having perforations 14 coaxial with anodes 6, as in Fig. 1, is provided with supporting wires 21 welded at opposite ends of a diameter of the disk bisecting the line between perforations 14, wires 21 being anchored to press 2 120

so that disk 11 is held firmly against the upper end of sleeves 4. In order to hold disk 11 from movement laterally to anodes 6 a wire is welded at each end to one of the wires 21 5 and extends around sleeves 4 in the form of a figure 8 thereby to hold them in fixed position. It will be noted that no rim is provided on the cathode 11 shown in Figs. 5 and 6, but it is to be understood that rims 17, 19 or 20 10 shown in Figs. 1, 3 and 4, respectively, may be provided thereon, if desired.

In the form of cathode shown in Figs. 7 and 8, the anodes 6 are mounted in similar relation to that shown in Fig. 1, sleeves 4 15 being shown schematically by dotted lines. A wing 22 midway between perforations 14 improves the operating characteristics of the rectifier and serves in part to prevent undesired discharges directly between anodes 6.

20 In Figs. 9 and 10 the cathode disk 11 is related to anodes 6 in a manner similar to that shown in Fig. 1. Wing 23 secured at one edge to disk 11, as by welding, is disposed at an acute angle with disk 11 in such a position 25 as to reach over perforations 14 and thus serves to concentrate the ionized gases near the surface of the cathode. The cathode structure shown in Fig. 11 differs from that shown in Fig. 10 in that a wire like tip 24 30 is provided fast to wing 23, the free end of the tip being coaxial with anode 6 and spaced slightly above perforation 14 on the opposite side of disk 11 from anodes 6.

Figs. 12 and 13 show a modified arrangement somewhat similar to that shown in Fig. 11. A pair of auxiliary tips 25 coaxial with anodes 6 are shaped from a single wire having its central portion 26 welded or otherwise secured to the top of cathode 11. Tips 40 25 serve to concentrate the heat and ionization near cathode perforations 14 and thus reduce the resistance of the gap between the cathode and anodes.

In Figs. 14 and 15, the parallel wires 27 45 serve as anodes extending along the active electron emitting surface of cathode 28, which may be hollow as shown, to facilitate baking by high frequency magnetic induction during manufacture. Stems 29 of glass or other 50 suitable insulating material, preferably adapted for withstanding high temperatures, surround the lower ends of anodes 27 and form protecting sleeves which localize the electron receiving area of the anodes to the 55 upper portions thereof. Cathode 28 is preferably coated with an electron emitting agent such as that used on cathode 11, Fig. 1. In any of the modifications of the invention, it is to be understood that the usual terminals, not 60 shown, may be provided at the base of the vessel for connection with the electrode leads, so that the base of the vessel fits into a socket in well known manner. The principles disclosed herein in connection with rectifiers are 65 not limited thereto, but are broadly appli-

cable to various forms of electric discharge devices employing ionizable gaseous substances.

In all of the above electrode structures the spacing of the electrodes is preferably greater than the mean free path of the gas within which the electrodes are immersed, although if desired the electrodes may be separated by distances less than the mean free path of the gas. It is to be understood that any one of 75 the cathode rims 17, 19 or 20, may be employed at the periphery of the cathode disks shown in any of the figures, thereby to stiffen the disks and to control the discharge between the electrodes. 80

The structures shown in the various figures, provide electrodes adapted for full wave rectification of an alternating current. Obviously one of the anodes and the corresponding cathode perforation and thimble may be 85 omitted or the circuit of one anode may be left open in order to provide a rectifier of only one half of an alternating current wave.

We claim:

1. In an electrical discharge device of the 90 gas filled type, an anode, a cathode spaced therefrom and having a turned up edge at the periphery thereof, and means localized on a portion of said edge for controlling the uniformity of the discharge between said 95 anode and cathode.

2. In an electrical discharge device of the 100 gas filled type, an anode, a cathode spaced therefrom and having a turned up edge at the periphery of the electron emitting portion thereof, said edge being dented in at least one place for controlling the discharge between said anode and cathode.

3. In an electrical discharge device of the 105 gas filled type, an anode, and a cathode spaced therefrom and having an electron emitting surface on one side thereof, said cathode having a reinforcing rim turned upon around said surface, said rim having a plurality of dented-in portions spaced apart therein for 110 controlling the discharge between said anode and cathode.

In witness whereof we hereunto subscribe our names this 18th day of December, 1926.
